UNITED STATES PATENT OFFICE.

ALLEN J. COLWELL, OF PROVIDENCE, RHODE ISLAND, ASSIGNOR TO COLWELL CIGAR MACHINE COMPANY, INCORPORATED, A CORPORATION OF DELAWARE.

MACHINE FOR MAKING CIGARS.

1,231,132.

Specification of Letters Patent. Patented June 26, 1917.

Application filed December 8, 1916. Serial No. 135,787.

To all whom it may concern:

Be it known that I, ALLEN J. COLWELL, a citizen of the United States, residing at Providence, in the county of Providence and State of Rhode Island, have invented certain new and useful Improvements in Machines for Making Cigars, of which the following is a specification.

My invention relates to that class of machines for making cigars known as bunching machines, and more particularly to the feeding mechanism thereof.

It is essential that the strips throughout their progress over the bed of the machine be maintained in perfect parallelism with each other transversely of the machine. This is difficult and not always successful after the initial shearing operation since in practice the strips are compressed more densely at one end than at the other by the shearing, with the result that from that point upon the machine bed the strips are not always fed in parallelism. An object of this invention is to overcome this trouble.

Other objects are to simplify the operation of the feed carriage, and reduce the number of parts of the same to a minimum; to conveniently position the release mechanism relatively to the feed carriage; and to insure such a prompt action of release mechanism as to prevent excessive compression of the bunch in the holder.

To the enumerated ends primarily my invention consists in such parts and in such combinations of parts as fall within the scope of the appended claims.

In the accompanying drawings which form a part of this specification—

Figure 1 is a top plan view, with parts broken away, of a sufficient portion of a bunching machine with my improvements added to enable the invention to be understood, the machine illustrated being that set forth in my prior United States Patent No. 1,175,125 dated Mar. 14, 1916,

Fig. 2, a longitudinal section of the same on line 2—2 of Fig. 1;

Fig. 3, a side elevation thereof,

Fig. 4, a perspective view of the feed carriage, parts being broken away,

Figs. 5, 6 and 7, sections respectively on lines 5—5, 6—6, and 7—7 of Fig. 1,

Fig. 8, a section on line 8—8 of Fig. 3,
Fig. 9, a section on line 9—9 of Fig. 2,
and

Fig. 10, a partial section on line 6—6 showing the parts distended.

Like reference characters indicate like parts throughout the views.

In bearings 15 in the frame 16 of the machine is the main shaft 18 which drives the mechanism. On the frame is the floor or run 20 upon the rear end of which is the mechanism for cutting or trimming the strips comprising the reciprocating side 65 plungers 22 and center plunger 23, the former being connected to rock shaft 24 by links 25 and levers 26; and the latter being loosely connected to the rock shaft 27 by link 28 and lever 30. Shaft 24 is rocked by 70 cam 32 on shaft 18, fork 34, connecting rod 35, and rock lever 36. Shaft 27 is actuated by cam 38 on the shaft 18, fork 39, connecting rod 41, and lever 42. While the three plungers advance in unison, the center 75 plunger travels some distance in advance of the others.

Upon the bed in advance of the plungers is the abutment comprising the blocks 43, bridge 44, cutter plates 45, and semi-elliptical blades 46, forming the space 47 through which the plunger 23 passes along the bed, as the plungers 22 contact with the blades to sever the ends of the advanced strips.

The strips advanced by the plunger are 85 further advanced along the bed by a feeding mechanism now to be described. Fast on each end of the rock shaft 27 is a segment 49 whose teeth 50 engage the teeth 51 of a rack bar 52. These bars are slidably mounted in 90 caps or guides 54 extending longitudinally of the frame at each side of the bed, and are reciprocated by the segments. Fast to the forward ends of the rack bars are plates 56 having an upturned finger 57 on the rear 95 end and a vertical lug 58 on the opposite end; the latter being preferably of greater height, and both forming the limits of a horizontal slot 59. Adjacent the plates 56 are plates 60 vertically movable in guides 61 100 upon opposite sides of the frame. The latter plates are vertically reciprocated by racks 62 held tightly against the plates 60 by tie rods 63 passing through vertical slots

64 in the frame. The racks engage toothed segments 66 on the ends of a rock shaft 67 mounted in the frame, fast to which is an arm 68 connected with a rod 69 carrying a fork 70 engaging a cam 73 upon the shaft 18. The plates 60 have horizontal slots 75 in which slide guide studs 76 upon the sides 77 of a frame 78 comprising a top 79 and a base 80, the latter having a transversely disposed series of teeth 81 upon its bottom face. Longitudinally slideable in the box or frame 78 is a preferably hollow block, slide, or frame 83, provided in its forward end with a horizontal series of longitudinally disposed slots 84. The portions of the slide intermediate the slots are forwardly projected and constitute fingers 85 with end prongs 86. Fixed to the rear end of the slide are vertical lugs 87 carrying screws 88 provided with adjusting nuts 89. Upon the top of the box 78, at its forward end, are pins 90 which are connected to the screws 88 by springs 91. Thus the slide 83 is normally drawn forward relatively to the frame 78.

25. The frame 78 has intermittent engagement with the plates 56 by means of laterally projecting members 92 upon its top extending into the plane of the guide fingers 58 of said plates. The horizontal movement 30 of the contact plates 56 and the vertical movement of the carrier plates 60 combine to impel the carrier frame in a rectangular path. The fingers 57 by contact with members 92 advance the frame, whose teeth 81 35 and the prongs 86 engage and carry forward along the run 20 the tobacco strips or sheet. Next, the plates 60 elevate the frame out of contact with the strips. Thereafter the lugs 58, in their retreat pressing upon the members 92, carry the frame in its elevated position to its rearmost limit, and the descent of the plates 60 lowers the frame to original position, with the members 92 in the path of the fingers 57, and with the teeth in engagement with the strips ready for the next 45 advance. These movements press the strips into the filler receiving box 94 at the end of run, after passing beneath the bars of the evening grid 95 fixed to the machine frame.

To prevent excessive density of the strips in the receiving box 94, it is necessary that when the resistance of the strips to the advance of the feed fingers 85 reaches a predetermined degree the pressure upon the strips be relieved or lessened. This is effected not only by the rearward yielding of the slide 83 relatively to the frame 78 by virtue of the springs 91, but also by preventing any further advance by either frame notwithstanding the continued reciprocation of the plates 56.

The mechanism whereby this purpose is effected is the following.

In the top of the carrier frame 78 is a transversely disposed guideway 96 inclosed by a plate 97. In the guideway are slidably mounted the members 92 provided with overlapping inner end portions 98 of reduced thickness, as shown in Fig. 6. The outer 70 extremities of the members have depending lugs 99 which, in normal or contracted position, are in the paths of the fingers 57 when the frame is in depressed position. Fast to intermediate portions of the members 92 are vertical ears 101 passing through oblong slots 102 in the plate 97. One ear has a smooth perforation 103, and the other ear has a threaded perforation 104. A bar 105 has a threaded end 106 in the perforation 80 104, while its other end passes loosely through the perforation 103. On this bar is also an adjusting nut 107 against which abuts a helical compression spring 108 surrounding the bar 105 and pressing against the opposite lug. Near the outer ends of the members 92 are studs 109 passing through slots 110 in the plate 97. These studs are engageable with fixed cams 112 upon the tops of the plates 60 in such a manner as to compress the members 92 against the pressure of spring 108 to their locked position as the frame 78 retreats, and to permit said members to distend laterally when they are released. The locking and release are effected by virtue of a finger or key 114 fast to the slide 83 extending through a slot 115 in the top of the frame 78. The end of this finger is square and is adapted to simultaneously enter two rectangular lateral cavities 117 in the overlapping portions 98 of the members 92 when said cavities register with each other. While the finger is in the cavities, the members 92 are locked in retracted position. When the finger is withdrawn, said members are distended to such an extent that the end lugs 99 are thrown outside the paths of the fingers 57 when the latter advance, as shown in Fig. 10, and thus the frame and slide remain quiescent. The obstruction which forces the slide 83 to yield removes the finger from the cavities to release the parts; and the cams 112 and studs 109 coöperate with the springs 91 to relock the parts.

Referring to the severed strips that are advanced along the run by the plunger 23, they are more loose at one end than at the other, and disposed slightly fan shaped rather than in absolute parallelism with each other. This is due to the fact that in the actual cutting operation the bunch of strips is rendered more condensed at one end. It is important that these strips should assume perfect parallelism with each other transversely of the run before they are engaged by the teeth of the feed frame 78. This straightening function is attained by the fol-

lowing device. Fixed to the rear ends of the plates 60 are rearwardly directed upwardly inclined arms 117 having bearing portions 118 upon their ends in which is journaled a shaft or pivot member 119 integral with a depending vibratory plate 120 whose sharp lower or operating edge 121 nearly contacts with the run 20 in the path of the strips when the plate is in vertical position, as shown in Fig. 7. This plate is somewhat yielding in the direction of travel of the strips or forwardly, resistance being afforded by a helical spring 123 upon the shaft 119 having its ends attached to or engaging a bearing portion 118 and the plate 120. The resistance of this plate to the strips in their travel disposes them in parallelism with each other. To prevent the strips piling upon each other during this operation a plate 125 is fixed to or integral with the bed and bridge 44 a sufficient height to permit the strips to pass thereunder and extending forwardly to a point adjacent the carriage 18. This plate is provided with a series of longitudinal slots 126 which terminate at their rear ends at a point immediately below the pivoted plate 120, forming resultant bars 127. The operating edge of the plate 120 has vertical cavities 128 to loosely receive the bars and allow said plate to swing into an upright position with its edge adjacent the run. A transversely disposed vertical guide plate 130 is fixed to the top of the plate 125 at the rear ends of the slots.

The operation of my device is as follows. The plates 60 in their reciprocation descend and force the operating edge of the plate 120, which rests against the guide plate 130 above the plate 125, down through the slots 126 to the position shown in Fig. 7, the sharp edge cutting cleanly through or between any strips that may be present. At this instant, the plunger 23 advances to perform the shearing operation, and at the end of this advance the plates 60 rise and suspends the plate 120 above the path of the strips till the next advance of the plunger.

I claim:

50 1. In a machine of the type set forth, the combination with a run, of a feed carriage on the run, a shearing plunger upon the run adapted to advance tobacco strips to the carriage, and means intermediate the plunger and carriage for yieldingly engaging the strips.

60 2. In a machine of the type set forth, the combination with a run, of shearing blades upon the run, a plunger slidably mounted on the run and movable through the blades to advance tobacco strips, and a plate arranged transversely of the run in the path of the strips.

3. In a machine of the type set forth, the

combination with a run, of a reciprocating shearing plunger mounted upon the run to advance tobacco strips, a vertically reciprocating straightening plate mounted on the run in advance of the plunger and movable toward and from the run, and a driving shaft actuating the plunger for reciprocating the plate.

4. In a machine of the type set forth, the combination of a run, a reciprocating plunger mounted on the run adapted to advance tobacco strips along the run, vertically reciprocating plates mounted upon the sides of the run, arms carried by the plates, a depending plate mounted in the arms in front of the plunger and movable toward and from the run in the path of the strips, means for reciprocating the plunger, and a driving shaft actuating with the plunger reciprocating means for operating the reciprocating plates.

5. In a machine of the type set forth, the combination with a run, of a reciprocating shearing plunger mounted on the run adapted to advance tobacco strips along the run, means for reciprocating the plunger, plates upon the sides of the run, arms carried by the plates, and a depending straightening plate pivotally mounted in the arms in front of the plunger extending to the run in the path of the strips.

6. In a machine of the type set forth, the combination with a run, of a reciprocating shearing plunger mounted on the run adapted to advance tobacco strips along the run, means for reciprocating the plunger, plates upon the side of the run, arms carried by the plates, and a depending plate yieldingly mounted in the arms in front of the plunger extending to the run in the path of the strips.

7. In a machine of the type set forth, the combination with a run, of a housing plate on the run comprising a series of longitudinally disposed rods, plates upon the run, arms supported by the plates, pivot members in the arms above the housing plate, and a plate upon the pivot members provided with marginal cavities to receive the rods.

8. In a machine of the type set forth, the combination with a run, of a housing plate on the run comprising a series of rods, a vertical guard member on the housing, vertically reciprocating plates on the sides of the run, means for reciprocating the plates, arms supported by said plates extending over the housing, a depending plate pivotally mounted on the arms provided with marginal cavities to receive the rods, and spring means upon the arms and engaging the plate to force said plate against the guard member.

9. In a machine of the type set forth, the combination with a run, of an abutment on

- the run provided with an opening, blades upon the abutment at the margin of the opening, a reciprocating plunger slidably mounted on the run movable through the opening, means for reciprocating the plunger, a housing plate on the run extending above the opening comprising horizontal rods, arms extending above the housing plate, means upon the run for supporting the arms, and a swinging plate pivotally mounted in the arms provided with marginal cavities to receive the rods.
10. In a machine of the type set forth, the combination with a frame and run, of horizontally reciprocating contact plates on the frame beside the run, means for actuating the plates, carrier plates on the frame beside the run provided with horizontal guideways, a carrier frame above the run slidably mounted in the guideways, a slide yieldingly mounted in the carrier frame, and expansion rods on the carrier frame in the path of the contact plates.
11. In a machine of the type set forth, the combination with a frame and run, of horizontally reciprocating contact plates on the frame beside the run, means for actuating the plates, said plates being provided with horizontal slots, carrier plates on the frame beside the run provided with horizontal guideways, a carrier frame above the run slidably mounted in the guideways, a slide yieldingly mounted in the carrier frame, and expansion rods on the carrier frame extending into the slots.
12. In a machine of the type set forth, the combination with a frame and run, of horizontally reciprocating contact plates on the frame beside the run, means for actuating the plates, said plates being provided with horizontal slots, a vertical finger on each plate at one end of the slot, a lug on each plate at the other end of the slot, carrier plates on the frame beside the run provided with horizontal guideways, a carrier frame above the run mounted in the guideways, a slide in the carrier frame, and expansion rods on the carrier frame extending into the paths of the fingers and lugs.
13. In a machine of the type set forth, the combination with a run, of reciprocating contact plates mounted on the sides of the run, means for reciprocating the plates, carrier plates upon the sides of the run, a carriage frame slidably mounted in the carrier plates above the run, a slide yieldingly mounted in the frame, rods slidably mounted on the frame transversely thereof, means for sliding the rods into the paths of the contact plates, and means for sliding the rods out of the paths of the contact plates.
14. In a machine of the type set forth, the combination with a run, of reciprocating contact plates mounted upon the sides of the run, means for reciprocating the plates, carrier plates upon the sides of the run, a carriage frame slidably mounted in the carrier plates above the run, a slide yieldingly mounted in the frame, rods slidably mounted on the frame transversely thereof, means for sliding the rods into the paths of the contact plates, and means for sliding the rods out of the paths of the contact plates.
15. In a machine of the type set forth, the combination with a run, of reciprocating contact plates upon the run, means for actuating the plates, carrier plates on the run, a carriage frame slidably mounted in the carrier plates, a slide yieldingly mounted in the frame, expansion rods slidably mounted on the frame movable into and out of the paths of the contact plates, resilient means for moving the rods in one direction, and cams for moving the rods in the opposite direction.
16. In a machine of the type set forth, the combination with a run, of reciprocating contact plates upon the run, means for actuating the plates, carrier plates on the run, a carriage frame mounted in the carrier plates, a slide yieldingly mounted in the frame, expansion rods slidably mounted in the frame transversely thereof normally extending into the paths of the contact plates, a spring for expanding the rods out of the paths of the contact plates, cams on the carrier plates for compressing the rods into said paths, and a finger on the slide adapted to lock the rods in compressed position.
17. In a machine of the type set forth, the combination of a carrier frame, a slide yieldingly mounted in the frame and movable longitudinally thereof, expansion rods slidably mounted in the frame, and disposed transversely thereof having their adjacent inner ends overlapping, said overlapping ends being provided with cavities adapted to register with each other when the rods are contracted, resilient means for expanding the rods, and a finger on the slide adapted to register in the cavities when the rods are contracted.
18. In a machine of the type set forth, the combination of a carrier frame, a slide yieldingly mounted in the frame, transversely disposed expansion rods slidably mounted in the frame with their inner ends overlapping each other, said ends being provided with cavities registering with each other, ears on the rods, a spring engaging the ears, and a locking finger on the slide detachably engaging the rods in the cavities.
19. In a machine of the type set forth, the combination of carrier plates provided with horizontal guideways, a carrier frame mounted in the guideways, a slide yieldingly mounted in the frame and movable longitudinally thereof, expansion rods slidably mounted in the frame, and disposed transversely thereof having their adjacent inner ends overlapping, said overlapping ends being provided with cavities adapted to register with each other when the rods are contracted, resilient means for expanding the rods, and a finger on the slide adapted to register in the cavities when the rods are contracted.

dinally thereof, transversely disposed expansion rods slidably mounted in the frame, ears on the rods, a spring engaging the ears to expand the rods, cam studs on the rods, and cams on the plates engageable with the studs when the rods are expanded.

In testimony whereof I have affixed my signature in presence of two witnesses.

ALLEN J. COLWELL.
